UNITED STATES PATENT OFFICE.

ERNEST C. MANKIN, OF KANSAS CITY, MISSOURI.

FLUSHING APPARATUS FOR LOW-DOWN CLOSETS.

SPECIFICATION forming part of Letters Patent No. 670,934, dated April 2, 1901.

Application filed June 23, 1900. Serial No. 21,263. (No model.)

To all whom it may concern:

Be it known that I, ERNEST C. MANKIN, a citizen of the United States, and a resident of Kansas City, Jackson county, State of Missouri, have invented a new and useful Flushing Apparatus for Low-Down Closets, of which the following is a specification.

My invention relates to flushing apparatus for low-down closets of that type having a double trap and an interposed air-space.

At present all low-down closets are provided with a jet to reliably start the siphonic action, which jet-passage by corrosion or otherwise frequently becomes stopped up, and as it is formed in the earthenware and in most cases cannot be cleaned the bowl is rendered useless and must be replaced by another.

My object is to provide an efficient flushing apparatus for low-down closets, wherein the jet is dispensed with.

The invention consists in certain novel and peculiar features of construction and combinations of parts, as hereinafter described and claimed, and in order that it may be fully understood reference is to be had to the accompanying drawings, in which—

Figure 1 represents a view, partly in vertical section and partly in elevation, of a low-down-closet flushing apparatus embodying my invention. Fig 2 is a section of the tank, taken at right angles to Fig. 1.

In the drawings, 1 is the bowl, provided with the superposed traps 2 and 3 and an air-space 4 between said traps.

5 is a pipe connecting the air-space with the tank 6, the upper end of the pipe being above the water-level of the tank.

7 is the pipe for supplying water from the tank to the bowl.

8 is a valve to close the upper end of pipe 7 and provided with a shoulder 9 on its stem. 10 is a guide-bracket through which said stem extends.

45 11 is a hand-lever at the outside of tank 6 and mounted on a rock-shaft 12 projecting into the tank. 13 is an arm upon said shaft within the tank.

14 is a chain connecting arm 13 with the valve-stem, the arrangement being such that the depression of lever 11 raises the valve from its seat to start the flushing operation.

15 is a passage projecting laterally from pipe 7 within tank 6 and below valve 8.

16 is a standard. 17 is a lever pivoted in 55 said standard and provided at one end with a float 18 and at its opposite end with the upwardly-projecting arm 19.

20 is a valve to close passage 15 and having its stem 21 pivoted to lever 17 forward of 60 the pivotal point of the latter.

22 is a supply-pipe for the tank.

23 is a valve controlling the supply-pipe.

24 is a pivoted lever connected to the valve, provided with a float 25 at one end, the arrangement being such that as the water-level falls to a certain point the accompanying movement of said float raises valve 23 and permits water to flow into the tank, but as the supply is less than the exhaust through the larger 70 pipe 7 the level of the water continues to fall.

26 is a tube depending into the air-tight tank 6 and provided with a perforated cap 27 and with a valve 28 below the cap.

29 is a bracket.

30 is a lever pivoted to bracket 29 and provided at one end with an arm 31 projecting up into tube 26 in line with the valve. 32 is a float upon the opposite end of said lever.

In the practical operation of said apparatus, the depression of lever 11, as hereinbefore stated, raises valve 8 to start the flushing operation of the bowl. As said valve moves upwardly shoulder 9 engages arm 19 of lever 17 and pushes said arm back and incidentally depresses float 18. As said shoulder clears said arm the float immediately rises and disposes arm 19 below the shoulder, consequently holding valve 8 open. The water escaping from the tank into the bowl creates a partial vacuum in the tank and a suction which instantly draws the air out of air-space 4 up into the tank and starts the siphonic action of the water in the bowl. As the water-level in the tank falls it is accompanied, of course, by float 32, which immediately after the siphonic action is started causes arm 31 of lever 30 to raise valve 28 and permit the air to escape up through perforated cap 27 and the registering vent-pipe. 90

(Not shown.) This float-operated mechanism for opening the check-valve and permitting the air to escape interrupts the suctional action up through pipe 5, which of course

- would continue to take place if valve 28 remained seated, and thereby prevents any possibility of water and contents being drawn up into and perhaps choking said air-pipe.
- 5 As the water-level of tank 6 is lowered float 25 raises valve 23 to admit water from the supply-pipe 22, which water, as valve 8 is still open, flows out to the bowl, thereby making unnecessary the employment of a large tank
- 10 6. When the water-level in the tank gets so low that float 18 drops and withdraws arm 19 from under shoulder 9 and raises valve 20 the valve 8 is reseated. The water-level now begins to rise because it enters very much
- 15 faster than it escapes through passage 15 to supply the after-wash or flush to the bowl, which supply is automatically cut off by the reseating of valve 20 at the proper time by the water-level in the tank restoring float 18 to its
- 20 original elevated position. The water continues to enter tank 6 until float 25 is reelevated sufficiently to reseat valve 23, and at the same moment float 32 is reelevated to the proper point to withdraw its arm 31 from engagement
- 25 with valve 28 to permit the latter to be reseated. As the water-level in the tank rises in the filling operation the air is compressed and raising valve 28 off its seat escapes through the perforated cap 27.
- 30 In practice the valve 28 may be of such type that the pressure of air alone will be sufficient to raise it from its seat; but by the use of the float it is obvious this action is rendered much more positive and reliable, the
- 35 principal function of float 32, however, being to break the suctional action of air up through pipe 5 shortly after the siphonic action is begun.

From the above description it will be apparent that I have produced a flushing apparatus for low-down closets which is positive and reliable in action, of simple, strong, and durable construction, and which embodies the feature of advantage enumerated as desirable in the statement of invention, and while I have illustrated and described the preferred embodiment of the invention I wish it to be understood that I reserve the right to make all changes properly falling within its spirit and scope.

Having thus described the invention, what I claim as new, and desire to secure by Letters Patent, is—

In a flushing apparatus for low-down closets, the combination of a bowl, a water-tank, a pipe 7 connecting the rim of the bowl with the lower part of the tank and provided with an offsetting-passage 15, a guide-standard, a valve for the upper end of pipe 7 having a vertical stem extending through said guide-standard, and a shoulder 9 on said stem, a lever and connections for raising said valve from its seat, a standard, a lever 17 pivoted thereto and provided at opposite sides of the pivot with a float and an upwardly-inclined arm 19, and a valve to close or open the offsetting-passage and having the upper end of its stem pivoted to said lever between the pivot and upturned arm, all arranged substantially as described.

In testimony whereof I affix my signature in the presence of two witnesses.

ERNEST C. MANKIN.
